PLASTIC INDUSTRIAL FILTER TRAY

Ernie G. Seggebruch, East Moline, Ill., assignor to
Ametek, Inc., New York, N.Y., a corporation of
Delaware

Filed Apr. 7, 1967, Ser. No. 6,582

Term of patent 14 years

(Cl. D55—1)

FIG. 1

FIG. 2

FIG. 1 is a perspective view of the top side of a plastic industrial filter tray, it being understood that the full line portion is repeated throughout the dotted line portion; and

FIG. 2 is a perspective view looking from the bottom of FIG. 1.

What is claimed is:

The ornamental design for a plastic industrial filter tray, substantially as shown and described.
